SEWER ROD POWER

Hubert R. Crane, Los Angeles, Calif.

Application December 1, 1937, Serial No. 177,589

3 Claims. (Cl. 15—104.30)

This invention is an apparatus for scraping, cleaning or otherwise working in sewer lines, pipe and conduit systems or other organizations in which there may be bores or passageways 5 tending to become clogged or fouled from various environmental or incidental causes.

Because of the resistance frequently met in the cleaning of sewer lines it is very desirable that a practical, motor-powered apparatus be provided for the rapid, efficient and safe rotation and advance of a flexible-rod sewer working tool into and along the bore of the sewer, and this object is met by the invention herein set out.

Further, an object is to provide a motor-powered means for rotatively driving the flexible rod at a speed of practical rate far in advance of that which is possible by manual effort.

More particularly, a purpose of the invention is to provide a power-take-off plant or unit which 20 will serve to rotate the rod and its bore working tool head at several of selective speeds according to the work in hand and the type of tool head employed on the flexible rod. Another object is to provide a combined portable, wheeled 25 vehicular power unit and flexible-rod tool and a mechanically driven rod section coupler, with means whereby to manually control the drive of the coupler, and to provide for change of rate of rotation thereof.

30 Additionally, an object is to provide a power plant including a prime motor in combination with means whereby the tool may be rotated at speeds much less than that of the motor shaft so that the motor may be operated at its most 35 efficient speed, and to enable to employ a relatively small motor in the outfit for economy in several aspects.

Also, an object is to provide for avoiding the direct attachment of the tool rod to the shaft of 40 the motor so that this is protected against serious strains to its bearings incident to the whipping of such rods while at work.

The invention consists in certain advancements in this art as set forth in the ensuing disclosure and having, with the above, additional objects and advantages as hereinafter developed, and whose construction, combination and details of means, and the manner of operation will be made manifest in the description of the annexed 50 illustrative embodiment; it being understood that modifications, variations and adaptations may be resorted to within the scope, principle and spirit of the invention as it is more directly claimed hereinbelow.

55 Figure 1 is a plan of a form of the apparatus

incorporating the invention. Figure 2 is a rear or handle-end view of the plant. Figure 3 is sectional detail of one of the coupler-driving, power take-off sleeves of the apparatus.

The present combination includes, and is intended for the rotation of, a sectional, flexible rod 2 to the forward or working end of which is attachable one or another of various types of bore working tool heads such as an auger 3, and which when cutting into detritus in the bore will 10 advance and pull the rod 2. The rod is of the type having hooked ends 4 for driving interlock with respective double-end couplers 5 which are designed for application of divers torque-effort tools. The coupler is here provided with a diametrical hole 6 for the reception of a pin 7.

It has been generally the practice to turn the rod 2 by hand power but this does not enable operation of the rod at most efficient speeds, nor is it always possible to advance the tool in 20 the bore with desired facility and safety.

In the present invention the rod driving coupler pin 7 is shown as fastened in a mechanically driven hollow shaft or sleeve 8.

This sleeve 8 is turnably mounted in suitable 25 bearings 9 of an appropriate frame 10 carrying a small prime motor 11; the frame and the motor being rigidly fixed to a hollow axle 12 having an extensible end section 13 forming a chassis on wheels 14.

The shaft section 13 is adjusted in the axle 12 for extension of its wheel to an outward degree to give desired stability to the plant while driving the rod 2, and fastened by a pin or key 15.

30 Fixed on the drive sleeve 8 is a large gear 16 constantly meshing with a pinion 17 fixed on a shaft 18 journaled in the frame 10 and having at its rear end a fixed change speed pulley 19 to which power is transmitted as by 40 a belt 20 from a change speed pulley 21 fixed on the motor shaft 22. By shifting the belt from one step of the shaft pulley 21 to another the speed of the intermediate pulley 19 may be readily varied as desired according to the work. 45

A device is provided to control the drive from the motor shaft 22 to the intermediate shaft 18 and as shown includes a lever 24 pivoted at 26 on the frame 10 and having a toe 27 engaging an arm 28 pivoted on shaft 18, or otherwise 50 as desired, and carrying at its swinging end a presser roller 29 which is depressed by the lever 24 against the belt 20 with sufficient force to cause the belt to drive the pulley 19 and its shaft 18; the lever being interlockable with a 55

rack segment 38 to hold the driving relation. If it is desired to stop rotation of the shaft 18 and its related coupling driving sleeve 8, and the hitched rod 2, the lever 24 is shifted to release pressure of the roller 29 on belt 28 to loosen it without drive on the pulley 19.

Thus the rod driving sleeve 8 is driven at a speed very much below that of the motor shaft 22.

A further change of speed of rotation of the flexible rod 2 is made available in the apparatus by the provision of a rocking bearing 32 pivoted at 33 on the side of frame 10 in a position parallel to the axis of the pinion pulley 21 of shaft 22. Rotatively mounted in the bearing 32 is an elongate hollow shaft or sleeve 8^a for reception of and in which may be pinned a drive coupler 5 of a rod 2 as above set forth as to shaft 8.

On one end of the sleeve 8^a there is secured a change speed or stepped pulley 34 to receive a complementary belt, as belt 28, rove thereto from the pinion pulley 21. The bearing 33 is connected by a link 35 to the lever 24 and when this is shifted on the rack 38 to throw the bearing outward the applied belt (shown in dotted lines) will be tightened and the drive sleeve 8^a will turn the attached rod 2 through the pinned coupler in the sleeve; it being understood that in such drive hook-up the transmission shaft 18 will be out of commission.

Shaft 18 is shown as hollow and this may be adapted for receiving and pinning a rod driving coupler 5 if so desired, thus affording still another speed or rod rotation.

The purpose of mounting the power plant on the wheeled chassis 12-14 is to enable the motor to be advanced toward the bore in which the tool head may be working and for this function the chassis is provided with a suitable handle 36.

Also a rearward leg 37 is provided for standing the chassis at rest, with or without operation of the motor.

It will be seen that the rod 2 may have additional sections added to either end projecting from the drive sleeve 8 without disturbing the drive coupler pinned in the drive sleeve.

When the rod 2 is driven by means of the transmission 34 and sleeve 8^a it can be interrupted at will and the sleeve stopped by throwing the lever 24 to the left and this not only will slack the applied belt (dotted lines, Fig. 2) to reduce the speed of rod rotation to the extent desired, but if the lever is pushed away far enough the pulley 34 will swing into stopping engagement with a fixed brake 38 and thus hold the rod still whilst the motor is running.

What is claimed is:

1. Sewer bore cleaning apparatus including a prime motored vehicle, a sectional flexible rod having a tool head at one end and provided with section couplings, and a mechanism driven by the motor and including a rod drive sleeve rotative at a speed reduced as to that of the motor and through which the rod is axially shiftable and having means positively locking with an interposed coupling to rotate it.

2. A sewer rod apparatus having, in combination, a sectional flexible rod, a coupling device in which one end of the rod is co-rotatively attached, and a power driven sleeve in which said device is co-rotatively fixed by a positive, interlocking key mounted in the sleeve.

3. In a sewer rod driving machine, a power transmission, a rod driving member rotative thereby, and a rod coupling device co-rotatively connected to said drive member by a positive drive key carried by said member and a complementary rod end positively interlocking with the coupling for co-rotation; said member consisting of a sleeve in which the coupling is axially mounted for interlock with the key.
